UNITED STATES PATENT OFFICE.

REBECCA E. HOOPER, OF HALF MOON BAY, CALIFORNIA.

SANITARY DRINKING-CUP AND DISPENSER.

1,111,962.

Specification of Letters Patent. Patented Sept. 29, 1914.

Application filed August 6, 1913. Serial No. 783,322.

To all whom it may concern:

Be it known that I, REBECCA E. HOOPER, a citizen of the United States, residing at Half Moon Bay, in the county of San Mateo and State of California, have invented new and useful Improvements in Sanitary Drinking-Cups and Dispensers, of which the following is a specification.

This invention relates to a sanitary drinking cup and container.

The object of the invention is to provide a device of extreme simplicity for storing a supply of foldable drinking cups in which they will be protected against accumulation of dust and contamination by handling, and which will always present a single cup for withdrawal.

In public places where it is intended that cups should be used but once a large number must be on hand within convenient reach of the water supply and means should be provided whereby they may be conveniently and quickly extracted for use, otherwise the main object, a cup for each user, could not be carried out.

The invention consists of the parts and the construction and combination of parts as hereinafter more fully described and claimed, having reference to the accompanying drawings, in which—

Figure 1 is a front elevation showing the container in position upon the supporting plate. Fig. 2 is a side elevation of same, partly broken away. Fig. 3 is a perspective view of the container, partly broken away. Fig. 4 is an enlarged section of the lower end of the container. Fig. 5 is a cross-section of the container. Fig. 6 is a plan view and side elevation of the drinking cup, showing it in the folded position. Fig. 7 is a perspective view of the cup showing it open for use.

Referring to the drawings: A indicates in general a drinking cup of desired shape which is adapted to be flattened out and folded, as indicated in Fig. 6. The cup is preferably made of a temporary water-proof paper, or like material, and may be constructed in any suitable manner.

B indicates a plate or bracket which is adapted to be attached to any convenient support near the source of water supply. Suitably secured to the plate by hinges 2 is a rectangular-shaped container 3, the lower end of which may be slightly curved,

as at 4, in an outward direction with relation to the supporting plate, and secured within the container, as at 5—6 and 7, in any suitable manner, is a pair of guide plates 8 and 9. The guide plates 8 and 9 extend through the whole length of the container. By referring to Fig. 4 it will be seen that sufficient space is left below the lower end of the guide plates and the bottom 10 of the container to permit a single cup 16 to be withdrawn.

The lower end of the front face of the container B is slotted, as indicated at 11, and the bottom of the container is cut away, as indicated at 12. For the purpose of filling 70 the container with folded cups, as indicated in Fig. 2, a sufficiently large opening 13 has been provided on the rear portion of the container. This opening extends lengthwise of the casing and practically leaves the rear face of the casing open to permit the insertion of the folded cups. This is accomplished by releasing a suitable form of latch, indicated at 14. The container may then be swung about the hinges 2 into the dotted line position, indicated at 15, to permit the insertion of folded cups through the opening 13. This opening is however closed the moment the container is swung back and locked in position with relation to the supporting 85 plate B, thus preventing the admission of any dust to the interior of the container.

In operation when filling the container it is only necessary to stack the folded or flattened cups, as indicated in Figs. 2 and 4. 90 This is accomplished by folding the lower point of the cup 16 inwardly as each one is placed in position. A suitable weight or pressure 17 is then placed on top of the stack of folded cups for the purpose of feeding the cups down through the container. The inwardly folded end of each individual cup will, when reaching the lowermost layer of the stack, have a tendency to spring out into the position indicated at 18, the cut-away portion 12 in the bottom of the container permitting the pointed folded end to project out through the bottom. A sufficient portion of the cup is thus projected through the bottom of the container to permit the withdrawal of the cup. The cup being withdrawn in the direction of the arrow a, through the slot 11, will immediately be replaced by another cup and the folded projection of same will immediately spring 110

out into the projected position in readiness to be withdrawn; the natural spring of the paper being sufficient to cause the folded end to unfold itself with relation to the cup.

5 The cap thus extracted may be slightly pressed from the folded sides into the open position, indicated in Fig. 7, where it may be filled with water for the purpose described.

The cup may be constructed of almost any 10 suitable form of paper, and it is not necessary to water-proof the paper, as the cup is used only once, and having been once used the paper becomes quickly saturated and would immediately part or burst if refilled.

15 It is thus practically impossible for several persons to use the same drinking cup when once extracted from the container. Each individual person is therefore obliged to extract his individual cup and any spreading 20 of contagious diseases is thus positively prevented.

The container constructed as here shown is simple in construction and positive in 25 operation, and by permitting the use of folded cups it can easily be seen that a great quantity of same may be stored within the container. The device may be constructed of any suitable material, and being practically inclosed at all times it can easily be 30 seen that contamination by handling is obviated and the admission of dust is practically impossible. The cups are therefore maintained in a sanitary condition no matter how long they may be stored within the 35 container. While a portion of the lower-most cup is always exposed to the atmosphere, this is of no consequence as the wide

or drinking end of the cup is within the container; no dust or germs can thus settle on that portion of the cup which comes in 40 contact with the person's lips.

Having thus described my invention, what I claim and desire to secure by Letters Patent, is:

A container for drinking cups which latter are folded so as to have a relatively contracted portion which provides a finger grip, consisting of a casing having a slot in its front side which slot alines with the casing bottom and is of a length greater than the 50 greatest length of the folded cup, said casing having a forwardly curved lower end so that the bottom thereof is arranged at an incline, the bottom of the casing having a cutaway part located at substantially the center of 55 the slot and communicating therewith, said cutaway part being of a size slightly larger than that of the contracted part of the cup whereby said contracted part of the cup is permitted to pass through the cutaway part 60 and to project below the casing bottom and in substantially a vertical plane, the cutaway part being of considerably less length than the greatest length of the folded cup whereby to necessitate removal of the body of the 65 folded cup through the slot and by a single movement in a straight line.

In testimony whereof I have hereunto set my hand in the presence of two subscribing witnesses.

REBECCA E. HOOPER.
